UNITED STATES PATENT OFFICE

ROY INNESS NORTH, OF HOOSICK FALLS, NEW YORK

ASH OR CIGARETTE RECEPTACLE

Application filed May 7, 1929. Serial No. 361,242.

This invention relates to ash receivers and particularly to ash receivers in the form of cups removably mounted in a holder.

One of the objects of the present invention is to provide a very simple, neat, ornamental, and effective ash receiver of this type in which the holder is made of resilient material and split at one point so as to resiliently clasp the ash receiver itself, thus preventing the ash receiver from rattling within the holder and holding it firmly in place against the jars and shocks to which it may be subjected where the receiver is used on an automobile.

Another object of the invention is to provide a device of this kind in which the split resilient holder has mounted upon it a suction cup whereby the holder may be supported.

Another object is to so form the cup as to provide an interlock between the cup and the holder, preventing the cup from rotating within the holder, and a further object is to so form the upper margin of the cup as to provide a notch so formed as to pinch the cigarette and when a cigarette is disposed transversely of the mouth of the cup.

Another object is to provide an ash receiver which is particularly adapted for use on automobiles, though capable of use in other situations.

My invention is illustrated in the accompanying drawing, wherein:—

Figure 1 is a side elevation of an ash and cigarette holder constructed in accordance with my invention;

Figure 2 is a top plan view of the structure shown in Figure 1;

Figure 3 is a vertical sectional view on the line 3—3 of Figure 2;

Figure 4 is a top plan view of the elastic ring or support, the cup being detached;

Figure 5 is a section on the line 5—5 of Figure 4;

Figure 6 is a fragmentary perspective view showing a modified form of the cup.

Referring to this drawing, 10 designates the holder proper which may be made of metal, celluloid, hard rubber or any other relatively stiff and resilient material. This is in the form of an annulus split at 11, the

upper portion of the split being wider than the lower portion for a reason to be later stated. The holder is formed upon its inside face with a shoulder 12 extending entirely around the holder, but terminating at the split 11 and with a projecting lug 13 projecting inward from the rim of the holder just above the shoulder 12.

Attached to the holder in any suitable manner is a suction cup 14 of any suitable or usual construction. While I do not wish to be limited to any particular material for this holder, I find that relatively heavy celluloid, hard rubber or bakelite is extremely good material.

The cup 15 is also formed of metal, hard rubber, bakelite, celluloid or the like and has a somewhat rounded or pointed lower end and gradually increases in diameter towards its upper end. The upper end of the cup is provided with the outwardly projecting rim of flange 16. This is interrupted at two points 17 and 18. The slot 18 is rectangular in form and inasmuch as the projecting flange is slotted at this point 18, it will be seen that when the cup is set in place, within the holder, the ends of the flange 16 may be disposed on each side of the lug 13, thus locking the cup therein from rotation. The interruption or slot 17 diametrically opposite the slot 18, when the slot 18 is engaged with the lug 13, alines with the opening or slit 11. This notch 17 constitutes means whereby a cigarette may be supported with its lighted end disposed over the cup, the cigarette under these circumstances, being pinched between the ends of the slot 17 and also between the ends of the slot 11 and thus held in this position.

I do not wish to be limited to providing the lug such as 13 upon the holder 10 as this lug might be formed upon the cup and the holder 10 be recessed to receive the lug.

In Figure 6, I illustrate the cup 15 as being formed below the flange 16 with an outwardly projecting longitudinally extending lug 19 which is adapted to fit within the split 11 and thus hold the cup from any rotation. In this case, the upper portion of the split 11 alines with the recess or slot 17 as before stated and

the cigarette may be supported in this slot so formed as before described.

While heretofore I have referred to this device as an ash receptacle, it will be understood that it may be used for holding cigarettes, matches or for any other purpose for which it is capable of use, though it is particularly adapted for automobiles.

I claim:—

- 10 A cup-shaped receptacle tapering toward its lower end and a stiff, resilient, annular support therefor having means for attachment to a wall, the support around the inner face of its upper edge being increased in internal and external diameter and being split at one point by a transversely extending slit, the slit being widened at its upper portion where it intersects that portion of the annulus having an increased diameter, the receptacle being insertible into the support and expanding it when so inserted, the upper margin of the receptacle being formed with a flange seating within the large upper portion of the support and being formed with a cigarette 20 receiving notch, the sides of the notch being adapted to bind upon a cigarette and hold it against movement, and interengaging means on the support and on the flange of the receptacle locking the receptacle from rotary 25 movement when fully inserted in the support and holding the receptacle with its cigarette notch in register with the enlarged upper portion of the slit extending across the support.
- 30 35 In testimony whereof I hereunto affix my signature.

ROY INNESS NORTH.
